POCKET AUTOGRAPHIC REGISTER

Migiel John Uline, Washington, D. C.

Application December 14, 1949, Serial No. 132,819

8 Claims. (Cl. 282—15)

1

This invention relates to a pocket register which is adapted for carrying in the pocket of a delivery man, a waiter on a pullman train or in a restaurant, or by any others, whereby a record is kept within the register of the original ticket or bill signed by the customer.

One of the principal objects of the invention is to provide a register of the autographic type which may be kept in the pocket or pocketbook of the user, and by which a permanent record is kept of a series of sales.

An additional object of the invention is to provide an autographic register of the type heretofore described having mechanism for feeding a plurality of sheets of paper past a viewing window which surrounds a table with means for feeding the paper so that one of the strips, preferably the original one, will be kept within the machine and one or more of the strips will be fed outwardly through a slot or other opening in the register.

A further object of the invention is to provide a pocket autographic register having a plurality of compartments and a writing table with means located below and preferably fastened to the writing table for locking the register and thereby preventing access thereto.

Yet another object of the invention is to provide a pocket autographic register having a removable top with a window in the top and a table located below the top and means forming part of a lock permanently fastened to the under side of the table whereby the top may be locked to the body of the register and unauthorized access to the register may be prevented.

Other objects will appear hereinafter throughout the specification.

In the drawings:

Figure 1 is a top plan view of the pocket register.

Figure 2 is a transverse sectional view of the register shown in Figure 1 taken on the line 2—2 thereof.

Figure 3 is a side elevation of the register shown in Figures 1 and 2.

Figure 4 is a vertical sectional view of the register taken on the line 4—4 of Figure 1 and

Figure 5 is a perspective view of a sheet of the paper used in the autographic register of this invention.

Heretofore it has been possible for delivery men who deliver ice and other commodities to falsify their records so that they may steal a large portion of the proceeds for the article delivered. Such delivery men are usually provided with a book containing an original and one or more copy

2

sheets between which are interleaved carbon sheets. Sometimes the under surface of the original is carbonized so that a separate carbon sheet is unnecessary. When such books are used the customer usually signs and pays for the commodity delivered, and a large number of deliveries are made by the same individual in one day. Under these circumstances, the customer usually files away the receipt and forgets about it unless he is called upon to pay for the goods by the seller, whereupon he produces the receipt to show that he has already paid. It is possible to circumvent this method of doing business by the delivery man accepting cash from each buyer for his deliveries. He then destroys the original record showing the amount of goods sold, cost thereof and to whom sold and converts the cash for his own use. It is very often difficult for the seller to keep an accurate check so as to be sure that the entire amount of money received by the delivery man is turned over to him, and sometimes the delivery man withholds many hundreds of dollars each month and destroys the original sales check as a part of his scheme to retain the money for his own use which he receives in selling his employer's goods.

It is also possible in dining cars of railroad trains and in restaurants and clubs for the waiter who serves the customer to destroy the bill of sale and retain the entire amount paid for the goods or services which have been purchased by the customer.

The device of the present invention makes it impossible for such employees to defraud the seller because there is a record kept in the machine which is locked upon which record each sale will be shown.

Referring to the drawings A indicates the register as a whole. The register which is of small size and comparatively flat, includes a top 1 having a rear end 2 and a forward end 3 which are downturned together with the side edges 4 and 5, which will be seen in Figures 3 and 4, also downturned.

Along the side edge 4 is a hinge 6 which hinges the top to the body portion 7 having a base 8.

The top is provided with a window 9 which, as seen in Figure 1, does not extend as far as the side edges 4 and 5. Permanently affixed to the base and side walls of the body portion is a substantially vertical wall 10 having a rearwardly and downwardly inclined portion 11, a U-shaped portion 12 which is extended beneath the window 9 to form a table 13 forming a surface for the paper when written upon. The top portion which terminates

in the upper edge of the body portion is offset at 14. All around this upper edge for receiving the downturned ends are sides 2, 3, 4 and 5 of the top 1.

Extending downwardly from one side edge of the table is a flap or tongue 15 having a locking aperture 16 which is adapted to be engaged by a suitable lock 17. This lock ordinarily will be operated by a key, not shown, but it will be understood that it may consist of a combination lock. A spindle 18 having a slot for winding the record sheet may be rotated by the knurled wheel 19 located outside of the register. A pawl and ratchet, not shown, may be provided to prevent retrograde movement of the wheel 19. The forward compartment of the body portion is defined by the wall 20 having upper nose 20a which separates the original from the carbon sheet and carbon papers which may be inclined as seen in Figure 4 and between this wall and the front 20 space 21 of the body portion is located the spindle 18. In space 21 for feeding the sheets of paper in alignment there is provided a shaft 22 having pin-wheels 23 mounted on the opposite ends thereof.

The Z-shaped pad 24 is provided with an upper forward edge 25. The paper is interleaved to provide an original upper sheet 26 forming the original, which sheet is wound within the compartment 21 on spindle 18. There is an intermediate sheet of carbon paper 27 and a carbon copy paper as indicated at 28.

It will be understood that these sheets, or at least sheets 26 and 28 will be provided on their side edges with suitable perforations for engagement of the pin-wheels 23 in order that the lines on these sheets may be kept in superposed relationship as the sheets are fed onto the table 13. In place of original sheet 26 and carbon sheet 27 there may be employed a single sheet 29 as seen in Figure 5, this sheet being provided with a plurality of apertures 30 for the pin-wheels 23 and contains a carbonized under surface 31. When using the construction shown in Figure 5, the sheet 29 is fed forward with the sheet 28 and after the bill has been made out the handle 19 is operated to feed the sheet to wind the sheet 29 around the spindle 18 and to feed the carbon sheet 28 out through the slot 32. It will be understood that when the carbon sheet comprises a separate sheet as indicated at 27, both sheets 27 and 28 will be sent through the slot 32. The slot 32 is provided with a tear-off blade 33.

From the foregoing description it will be appreciated that when a sale is made, the salesman by rotating the knob 19 in a clockwise direction feeds the manifolded paper across the table 13 until a fresh blank is provided as indicated in Figure 1. The seller's name, the amount of goods sold and price are usually written down on the specified portion of the strip, after which the strip is fed forward by rotating the knob 19 in a clockwise direction until a new portion or bill blank is exposed. During this time the original is wound on the shaft 18 and the carbon sheet and carbon paper are fed downwardly and are torn off by the blade 33.

When an additional sale is made the operation is repeated.

At the end of a day's run, or the completion of the series of selling operations the pocket register is turned over to the seller or his representative, who produces a key and unlocks the register. Each separate sale will be found on the record sheet which has been wound on the spindle 75

18 and these may be kept with the cash which has been turned over to the owner or his representative by the seller following the series of sales which have been made.

I claim:

1. An autographic register having in combination a body portion having a compartment for storing manifolded paper, a top, means for hinging said top to said body, said top having a window, a plurality of partitions in said body portion, one of said partitions including a vertical wall attached to said body portion, said wall having a rearward extension, a U-shaped portion and a continuation of said U-shaped portion, said continuation forming a platen and locking means for feeding said manifolded paper across said top, another of said partitions including a wall extending substantially transversely across said body portion, said wall having a nose for separating the original sheet from a carbon sheet of said manifolded sheets, said body portion having a base, said base having a tear-off blade.

2. A pocket autographic register comprising an obstructed surfaced article including a body portion having sides with one of said sides having a circular indentation for the reception of a knurled operating handle, a top hinged to said body portion and having a window therein, a combined table top, partition wall and paper guide comprising a single sheet of metal having a wall extending at right angles to said table top, said paper guide extending beneath said table top and having a U-shaped portion connecting said paper guide to said table top, a compartment for a record sheet as it is fed over said table located on the opposite side of said table from said U-shaped portion, and means for feeding paper from a paper pack located in said body portion adjacent said partition wall across said table top including feeding means in said compartment, and a knurled knob in said circular indentation operatively connected to said feeding means.

3. An autographic register having in combination a body portion having a plurality of compartments, one of said compartments being for storing a plurality of work sheet strips, means dividing said one compartment from another compartment, said dividing means comprising a wall having an extending portion for guiding said strips from said one compartment, and a continuation of said extending portion, said continuation forming a platen, means for moving said strips over said platen and means in said other compartment for aligning said strips as they are moved, a third compartment, said platen extending over substantial portions of said one and said other compartment and means adjacent said aligning means for separating the sheets of each strip whereby at least one of said separated sheets enters said other compartment and another of said separated sheets enters a third compartment.

4. An autographic register having in combination a body portion having a plurality of compartments, one of said compartments being for storing a plurality of work sheet strips, means dividing said one compartment from another compartment, said dividing means comprising a wall having an extending portion for guiding said strips from said one compartment, and a continuation of said extending portion, said continuation forming a platen, means for moving said strips over said platen and means in said other compartment for aligning said strips as they are

moved, said platen extending over substantial portions of said one and said other compartment and means adjacent said aligning means for separating the sheets of each strip whereby at least one of said separated sheets enters said other compartment and another of said separated sheets enters a third compartment, said other compartment having a slot and said third compartment having means about which said other of said separated sheets are rolled.

5. An autographic register having in combination a body portion having a compartment for storing manifolded paper, a top having a window, a plurality of partitions in said body portion, one of said partitions including a substantially vertical wall attached to said body portion, said wall having a rearward extension, a substantially U-shaped portion and a continuation of said U-shaped portion, said continuation forming a platen, means for feeding said paper across said top, and another of said partitions including a wall having a nose for separating the original from a carbon sheet of said manifolded paper.

6. A tamper-proof autographic register having in combination a housing provided with a plurality of compartments, one of said compartments being for storing a plurality of work sheet strips, each strip comprising an original sheet and duplicate sheet with carbon therebetween, a second of said compartments having an opening therein through which one of said sheets may pass to the exterior of the housing, a platen extending in said one and second compartments, means for feeding said strips from said one compartment over said platen, and means for separating said strips after travel over said platen whereby the other of said sheets is directed to a third compartment and said one sheet is directed towards said second compartment, said third compartment having means for storing said other sheet, said separating means and said feeding means coating to prevent tampering of said other sheet and to permit entry of the one sheet in said second compartment whereby upon further operation of said feeding means, it is discharged through said opening.

7. A tamper-proof autographic register having in combination a housing provided with a plurality of compartments, one of said compartments being for storing a plurality of work sheet strips, each strip comprising an original and duplicate with carbon therebetween, a second of said compartments having an opening therein through which the duplicate may pass to the exterior of the housing, a platen extending in said one and second compartments, means for feeding said strips from said one compartment over said platen, and means for separating said strips after travel over said platen whereby the original

is directed to a third compartment and said duplicate is directed towards said second compartment, said third compartment having means for storing said original, said separating means and said feeding means coating to prevent tampering of said original sheet and to permit entry of the duplicate in said second compartment whereby upon further operation of said feeding means, it is discharged through said opening, said second compartment having a tear-off blade at said opening and said means for separating said strips comprising a partition dividing said second and third compartments, said partition having a nose portion for engaging said strips.

10 8. A tamper-proof autographic register having in combination a housing provided with a plurality of compartments, one of said compartments being for storing a plurality of work sheet strips, each strip comprising an original and duplicate with carbon therebetween, a second of said compartments having an opening therein through which the duplicate may pass to the exterior of the housing, a platen extending in said one and second compartments, means for feeding said strips from said one compartment over said platen, and means for separating said strips after travel over said platen whereby the original is directed to a third compartment and said duplicate is directed towards said second compartment, said third compartment having means for storing said original, said separating means and said feeding means coating to prevent tampering of said original sheet and to permit entry of the duplicate in said second compartment whereby upon further operation of said feeding means, it is discharged through said opening, said platen having an extension in said one compartment forming a combined guide for said strips and partition for dividing said first and second compartments.
